UNITED STATES PATENT OFFICE

2,030,454

HUMIDIFIER APPARATUS

Leo Kresser, Springfield, Mass., assignor to United
American Bosch Corporation, Springfield,
Mass., a corporation of New York

Application December 15, 1934, Serial No. 757,645

5 Claims. (Cl. 261—91)

This invention relates to humidifying apparatus and more particularly to apparatus for automatically maintaining a predetermined moisture content in the surrounding atmosphere. The humidifier is intended for use in heated buildings and households where the atmospheric moisture content commonly falls below healthful levels. Many industrial processes likewise require operation in a moist atmosphere. The humidifier presented in this invention is automatically controlled in response to the moisture content of the air, and is readily disassembled for inspection and cleaning.

An object of this invention is to provide a humidifier which is more efficient in operation and simple in construction.

Another object is to provide a humidifier having a centralized control apparatus removable as a unit.

20 A further object is to provide a humidifier which is more silent in operation.

Other objects and advantages will in part be obvious and in part specifically stated when the following specification is read in connection with the drawings in which Fig. 1 is a sectional view of the apparatus; Fig. 2 is a top sectional view thereof; and Fig. 3 is a front view of the control box.

Referring in more detail to Fig. 1, the numeral 1 represents a cabinet containing the entire apparatus. Positioned within the cabinet 1 is a water tank 2 which has a cast, annular supporting ring 3 attached to the upper rim thereof. The ring extends inwardly toward the central axis of the tank and carries on its upper surface three projecting seats 4. Positioned on these seats is a sheet metal annulus 5 having an upturned outer flange 6. The inner circumference of the annulus 5 has attached thereto an atomizing grid comprising a number of closely spaced vertical vanes 7. A vane ring 8 is fixed to the tops of the vanes 7 and acts as a brace to prevent relative movement and vibration. Also attached to the inner circumference of the annulus 5 is a strainer spider 9, supporting a tubular copper mesh strainer 10 which extends downwardly almost the full depth of tank 2. Extending radially inward from the wall of the strainer 10 are baffle plates 11 which prevent any circular motion of the water within the strainer. Secured to the outer wall of the strainer 10, and above the water level, is a dished flange 12 for catching any drip from the atomizer structure and preventing the noise caused by drops striking the main body of water.

55 Each of the seats 4 on the supporting ring 5 is

bored to receive a post 13 which carries the weight of the motor 18 and suspended parts. The post is reduced in diameter at its upper end which carries a rubber bushing 14. An arm of the tripod spider 15 has an opening which fits over the bushing 14. A rubber washer 16 and a metal washer 17 may be subsequently placed on the reduced end of post 13 and overlying the spider arm, the assembly being secured by a cotter pin through the post. A capacitor motor 18 is mounted on spider 15 with the armature shaft 19 vertically positioned, and is provided with a waterproof frame or casing. A collar 20 is secured to the end of shaft 19. Projecting downwardly from the collar and coaxial with the motor shaft 19 is a water elevating tube 21 and positioned within the lower end of the tube is an agitator plate 22. The agitator consists of a flat metal plate extending from one inner surface of the tube 21 to the opposite surface. The collar 20 also carries a horizontally extending atomizing disk 23 and a spider member 24 having fan blades 25. A cover 26 of special noise reducing qualities directs the humid air around the motor 18 to the outlet at the top of the machine. The cover 26 is formed with a double wall the inner of which may be perforated, and the intervening space is filled with a sound absorbent fibrous material 27. All tendency toward drumming or resonance vibration of the cover is thus prevented and noises produced by the motor and atomizer are minimized. The outer wall of the cover 26 extends downward to meet the upturned flange 6 of the annulus 5 and the cover is held in place by hook members 28 riveted to the skirt thereof and engaging posts 29 set along the outer rim of the supporting ring 3. Extending across the lower part of the cabinet 1 is a shelf 30 secured to opposite side walls by rubber insulated fastening members 31 which prevent the transmission of vibration between the parts. Secured by resilient mounts 32 to the shelf 30 and directly under the center of the tank 2, is a small electric fan 33. A deflector 34 is placed around the fan and directs air upwardly against the bottom of the tank 2 whence it flows outward and upward between the tank and walls of the cabinet 1. At the top of the cabinet and surrounding the humid air outlet 35 is a metal grille 36 which permits the humid air to be enveloped in dry air supplied by the fan 33, insuring complete assimilation of the entrained moisture.

In the operation of the machine, water flows by centrifugal action up the inner wall of the elevating tube 21, past the collar 20 to the upper sur-

face of the atomizing disk 23. Drops of water are thrown off the disk with a speed corresponding to its peripheral velocity and impinge against the tangential atomizing vanes 7, producing a fine mist. Air enters the space between the lower surface of the annulus 5 and the upper surface of the supporting ring 3, the seats 4 maintaining a clearance between these surfaces. The fan blades 25 direct the air against the vanes 7, where it picks up the mist and flows upwardly as indicated by the arrows, between the cover 26 and motor 18. Upon issuing through the outlet 35, it is enveloped in dry air as before explained, and no individual droplets remain to be deposited upon walls or furniture.

Mounted in the upper part of the cabinet 1 in the dry air stream is a control box 37 which automatically completes the motor circuits when the atmospheric moisture content falls below a predetermined level. As best illustrated in Fig. 3, the control box contains a humidistat element 38 with a control adjustment 39 which determines the operation point of the assembly. A spring arm 40 maintains the expansible element 38 taut, and upon its expansion the operating pin of switch 41 is depressed. The power circuit is then through the supply plug 42, the closed main switch 43, the humidistat switch 41, to the motor outlet receptacles 44 and 45 and the capacitor lead 46. An auxiliary or emergency switch 47 is placed in parallel across the contacts of the humidistat switch 41 to provide a shunt circuit permitting operation of the apparatus at will, and independent of the automatic control. As shown in Fig. 2, the emergency switch 47 is normally protected against unintentional operation by a removable thimble 48 which covers it. As best illustrated in Fig. 1, the outlet 44 supplies the humidifier motor 18, the outlet 45 supplies the fan motor 33, lead 46 connects the capacitor 49 in the field circuit of motor 18, and cable 42 connects with the alternating current mains. It will be seen that all the critical elements and circuits of the humidifier are concentrated within the control box and in case of failure, the box may be removed as a unit and replaced with a new one. Servicing is quickly and efficiently accomplished and with a minimum of annoyance to the owner of the machine.

Many changes and modifications may be made by anyone skilled in the art without departing

from the spirit and scope of the invention as defined in the following claims.

What I claim and desire to secure by Letters Patent of the United States is:

1. In a humidifier, a water tank, an atomizer in communication with said tank, a motor driving said atomizer, means for establishing a stream of moist air surrounding said motor, means for establishing a stream of dry air substantially concentric with said moist air stream, and a sound absorbent partition separating said air streams and positioned adjacent said motor.

2. In a humidifier, a water tank, an atomizer in communication with said tank, a motor driving said atomizer, means for establishing a stream of moist air surrounding said motor, means for establishing a stream of dry air substantially concentric with said moist air stream, and a partition separating said air streams and positioned adjacent said motor, said partition including a sound absorbent material.

3. In a humidifier, a water tank, an atomizer in communication with said tank, a motor driving said atomizer, means for establishing a stream of moist air surrounding said motor, means for establishing a stream of dry air substantially concentric with said moist air stream, and a partition separating said air streams and positioned adjacent said motor, said partition comprising two spaced walls having a sound absorbent material therebetween.

4. In a humidifier, a water tank, an atomizer in communication with said tank, a motor driving said atomizer, means for establishing a stream of moist air surrounding said motor, means for establishing a stream of dry air substantially concentric with said moist air stream, and a partition separating said air streams and positioned adjacent said motor, said partition comprising two spaced walls having a fibrous material therebetween.

5. In a humidifier, a water tank, an atomizer positioned above said tank, a motor positioned above and drivingly connected with said atomizer, means for producing an upward flow of moist air from said atomizer, a cabinet having walls spaced from said tank and motor, means for producing an upward flow of dry air adjacent the inner surfaces of said walls, and an upwardly extending sound absorbent partition secured adjacent said motor and separating said dry and moist air flows.

LEO KRESSER.

DISCLAIMER

2,030,454. —*Leo Kresser*, Springfield, Mass. HUMIDIFIER APPARATUS. Patent dated February 11, 1936. Disclaimer filed June 12, 1937, by the assignee, *United American Bosch Corporation*.

Hereby enters this disclaimer to claims 1 and 2 of said patent.
